COLLOID MILL

Benjamin Zober, Brooklyn, and Thomas Garvey,
Long Island City, N. Y.

Application May 3, 1935, Serial No. 19,632

5 Claims. (Cl. 83—7)

The main object of this invention is to provide a colloid mill in which horizontal or vertical rotor stones and other members cooperate with oscillating stators.

Another object of the invention is to provide a colloid mill which is so constructed as to obtain a uniformity of film thickness of the medium being ground in accordance with the necessity to prevent undue wear scoring of the rotor and stator surfaces and also to combine the hydraulic shear of the colloid mill with the shearing action of the attrition mill.

Still another object of the invention is to provide a colloid mill which is so constructed as to limit a very large amount of vibration so that the mechanical features of the colloid mill are proportionately and efficiently increased.

The above and other objects will become apparent in the description below in which characters 20 of reference refer to like-named parts in the drawings.

Referring briefly to the drawings Figure 1 is a longitudinal, sectional, elevational view of the preferred type of colloid mill.

Figure 2 is a top plan view of Figure 1.

Figure 3 is a partial, sectional, elevational view of a modified type of colloid mill.

Figure 4 is a plan view of a reenforced sintered stone showing how said sintered stone is fused 30 into dove-tailed ribs of holder.

Figure 5 is a cross-section view on line 5—5 of Figure 4 of same stone-holder and stone.

Figure 6 shows a sectional view at line 6—6 of Figure 4.

Referring in detail to the drawings the numeral 35 10, indicates an inlet head which is driven by an eccentric sleeve 11. A bearing 12, is provided which is made adjustable by being threaded in the housing 32, of the device. This bearing 12, is 40 adjusted by means of a hand lever 13. Said bearing 12 is adjusted by means of said hand lever 13 rotating said bearing 12. The downward motion of the bearing 12, transmits pressure thru the medium of a thrust bearing 15, eccentric 45 sleeve 11, and a self aligning thrust bearing 16. The thrust bearing is provided for the accommodation of the oscillating inlet 10, and the water cooled oscillating stator stone 17. A pinion gear 18, driven by means of motor or a belt or other 50 desired apparatus rotates a beveled gear 19. Said beveled gear 19, rotates the eccentric sleeve 11. This gear 19, is secured to member 11, thru means of a key 20, which latter is secured in place in a suitable groove by a screw 21. The gear 19, 55 has a ring 22, secured thereto by screws 23, and

this ring retains the gear in position on member 11. The key 20, is free to move vertically in its channel in the gear 19, when this movement is desired. The eccentric sleeve 11, is retained in place by a threaded collar 24, which engages said eccentric sleeve intermediate its length. Said threaded collar 24, is locked in place by a plurality of securing means such as screws 25. The collar 24, is provided with a thrust ring 26. The oscillating inlet head is secured in place by a threaded flange 27, and has a thrust ring 28 between said threaded flange 27 and eccentric sleeve 11, and said threaded flange 27 is locked in place by a screw 27a. The so called outboard bearing 29, rigidly supports the eccentric sleeve 15 10 11, in which the latter is journaled. Member 29, is secured to the casing 30, by means of screws 29a. Said casing 30, is mounted upon the housing or bearing support 14, by screws 31. Said housing 14, is attached to the stator housing 20 32, by screws 33. A bonnet 34, is attached to the eccentric sleeve 11, by set screws 35. A tail rod 36, is guided and retained in place by a forked rocker shaft 37. A forked rocker shaft 37 rocks in the stator housing 32, and is secured 25 in place by a collar 38. A dust cap 39, is attached and secured to the oscillating inlet head 10, by suitable screws 40. The stator stone 17, is retained in a dished out holder 41, which is annular 30 in shape. The dished out stator holder 41, is retained in place by a ring 42. Said ring is secured to the stator holder by suitable means. A conical deflecting hood 43, is secured to the lower portion of the oscillating inlet head 10, by any desirable means.

Figure 1, illustrates a longitudinal, elevational view and shows a main drive shaft 44, which may be driven by a source of energy such as a motor which latter may be directly connected to the lower end of the main drive shaft 44. 40 Said drive shaft 44, rotates a rotor casing 45, thru the medium of a T-headed stud 46. The stud 46, engages a key way in hub 47, which in turn is driven by drive shaft 44, by means of set screw 48. The stud 46, rotates a universal joint 49, which engages a key way 50, in the rotor. A rotor spring 51 or rubber cylinder, of substantial tension permits axial movement of the rotor member 45, on the drive shaft 44. The rotor disc holder 52, is seated upon member 45, and is actuated in a rotatable path thereby. This disc holder 52, is directly connected to the rotor member 45, by a dowel or other suitable pin 53. Said rotor 45, is adapted to float axially on self aligning bearings 55. This self aligning bearing 55

55, is of the usual construction in this type of device and is secured to the drive shaft 44, by a lock nut 54. A dust sealing cap 56, is attached to the rotor by screws or other means 56a. The 5 rotor stone holder 52, is secured to the rotor 45, by threaded stud 58. The rotor stone 59, is fused or sintered into re-inforced stone-holder 52. This stone is of the controlled structure type, wherein the ratio of voids or interstices to aggregates is greater than in a natural stone. A flinger 60, of outwardly flared shape is mounted upon the side or periphery of member 45, and is attached to this member by suitable screws. A radial thrust bearing 61, is secured to the drive 10 shaft 44, by a combination oil flinger and lock nut 62. An oil retaining sleeve 63, is pressed into the material of the rotor housing oil reservoir. The thrust bearing 61, is seated in the rotor housing 64, and is held in place by the dust cap 65. 15 The dust cap 65, is secured in place by suitable screws, to the rotor housing 64. A radial thrust bearing 66, is secured to the drive shaft 44, by combination oil flinger and lock nut 67. The radial thrust bearing 66, is adapted to float in the 20 rotor housing 64. The helical spring 68, is adapted to urge the retaining ring 69, downwardly in the direction of the thrust bearing. Said retaining ring bears on the radial thrust bearing 66, and retains the same in aligned position. The oil 25 reservoir cap 70, is mounted upon the rotor housing 64, in suspended position by screws 71. An oil retaining sleeve 70B, is sweated into the aperture formed in the reservoir 70, in a leak proof manner. A motor not shown but housed in suspended position beneath the shaft 44, is used to 30 drive the device. A plurality of spill ways 72, are attached to the rotor housing 64, by suitable screws 73.

In the modified type of construction shown in 40 Figure 3, a colloid mill is shown embodying the identical principle of the mill shown in Figure 1. Figure 3 illustrates a vertical section of a vertical mill. In Figure 3, the oscillating stator 74, is similar to that in Figure 1, except for the fact 45 that a plurality of coil springs surmounts the stator holder 75. These springs indicated by the numeral 76, urge the stator holder 75, and stone downwardly in floating axial position. A second series of springs 77, presses the packing ring 50 against the stator stone holder 75, so as to prevent entrance of the material into the clearance space. This is a departure from the construction shown in Figure 1, in which the stator stone holder is 55 stationary with reference to the oscillating inlet head 10. Figure 3, also illustrates a self aligning rotor assembly similar to Figure 1, except that the rotor 78, does not float axially on self aligning bearing 79. The universal joint 80, driven by a stud 81, drives the rotor 78. The rotor spring 60 81, the T-head 46, and the driving hub as shown in Figure 1, are eliminated from the design shown in Figure 3. In Fig. 1 and Fig. 2 stone holders may be provided with ribs as in Figs. 4, 5 and 6 so that the stone may be entered into the spaces 65 between the ribs or that the stones pressed into place in the holder while still plastic, and the bond may then be fused thru temperature means or by sintering a suitable stone in a molten condition into these spaces. The object of 70 enforcing the stone is to permit a much higher rotational speed than that at which ordinary stones may be operated safely. This high speed is necessary to cause deflocculation and dispersion in various materials. It also creates an intensive 75 turbulent scissors action, in combination with

hydraulic shear, brought about by eddy currents formed in the interstices in the stones, without generating excessive heat as is the case with grooved rotors and stators in roughened surface machines.

In operation the colloid mill functions as follows: The beveled gear 19, is rotated by the pinion gear 18, in some desirable manner. Rotation of these two members causes the eccentric sleeve 11, to be turned, the beveled gear 19, being secured 10 slidably to member 11, by a key 20. Rotation of the eccentric sleeve 11, imparts an oscillating motion to the inlet head 10. The inlet head 10, is a running fit in the eccentric sleeve 11. The stator stone 17, is securely attached to the oscillating inlet head 10, and is therefore given an oscillating motion which can best be described as a reciprocal motion, similar to an eccentric strap. This movement imparts to the surface of the stator stone 17, and the rotor stone 59, a variable 15 motion identical to that used in lapping two metal surfaces. The lapping process maintains the trueness of the grinding surface to both the stator and rotor stones, the trueness being necessary to obtain uniform film thickness. Obviously with a motion of this kind where the stator stones change their position in a variable manner, the grinding surfaces are prevented from becoming tracked, which causes erosion of the grinding surface and prevents the surfaces of the 20 stones from loading with material and glazing. The self aligning thrust bearing 16, is adapted to distribute the thrust load in an even manner and prevents lateral movement of its related parts. The tail rod 36, which is attached to the oscillating inlet head 10, is adapted to guide the 25 oscillating head 10, in an oscillatory path. A water pocket 79a, is formed above the stator stone and thru means of inlet pipes not shown will cool the stator stone and absorb a large part of the 30 heat developed in the grinding process. The deflecting hood 43, is adapted to direct the material leaving the grinding zone toward the water cooled portion of the housing. Inlet and outlet pipes not shown on drawings convey water to and from 35 water jacket in housing 64. The mill is constructed in a divided manner so that the stator housing may be rotated about a hinge 40a, in order to lift the upper portion of the mill approximately 120 degrees, in order to facilitate cleaning 40 of the interior of the rotor housing and all surfaces exposed to the ground material as shown in Figure 1.

A uniform pressure of the rotor grinding surface on the film of material is obtained by advancing the stator stone 17, axially toward the 45 rotor 45. The stator stone may be adjusted axially by turning threaded member 12 in the proper direction so as to raise or lower member 10, thereby lifting the stator stone 17. In this 50 manner the rotor spring 51, is compressed and the tension of said spring is transmitted to the universal joint 49, and then communicated to the rotor thereby finally urging the grinding surface of the rotor stone 59, into co-operating contact with the grinding surface of the stator stone 17. The rotor 45, floats axially on a self aligning bearing 55. This self aligning bearing while constraining the rotor 45, to rotate about the center coinciding with the axis of the drive shaft 44, yet 60 permits the grinding surface of the rotor to rotate in a true plane parallel to the grinding surface of the stator 17, thereby compensating for any variation in distance between these two surfaces with what would otherwise exist. The uni- 65 70 75 75

versal joint 49, which connects the T-head stud 46, with the rotor 45, in conjunction with the self aligning ball bearing 55, or other means prevents any misalignment of the main drive shaft 44, from being communicated from the driving shaft of the rotor which would consequently throw said grinding surface out of parallel with the grinding surface of the stator. This spring tension in combination with the self aligning features, which the universal joint and self aligning bearing imparts to the rotor, is adapted to maintain a uniform film thickness. The spring tension also automatically compels constant pressure on the film, unaffected by shaft elongation due to higher temperature or by change in the viscosity of the material being ground. Said spring tension in conjunction with the self aligning rotor also permits the passage of any foreign material without damage or injury to the grinding surface of the rotor and stator stones. The amount of tension applied to the rotor spring 51, is determined by the viscosity of the material and the fineness of the grind desired. The flinger 60, is provided to prevent access of the material into the rotor hub clearance. The T-head on the stud 46, moves axially in a slot in the drive hub when the spring is compressed or released, while running. While at the same time the drive hub 70a, drives the T-head stud 46. Stud 48, drives the hub 70a, from the drive shaft 44. The springs 68, bearing on the retaining ring 69, apply a slight thrust load on the radial thrust bearing 66, to provide axial play of the drive shaft 44, from setting up vibration. This thrust bearing 35 also prevents longitudinal expansion due to heat of the drive shaft 44, from creating a thrust load on bearing 66.

It is to be noted that certain changes in form and construction may be made without departing from the spirit and scope of the invention.

We claim:

1. In a colloid mill, a longitudinal inlet head, a stator stone secured to said inlet head, a sleeve having an eccentric aperture movably receiving said inlet head, a forked member, a tail rod unitary with said inlet head registering in said forked member for retaining said inlet head in oscillating position when said eccentric sleeve is rotated, and an angular deflecting hood unitary with said inlet head and stator stone, for deflecting the material being ground, a rotor provided with a rotor stone located beneath said stator, a drive shaft having an axially bored upper portion rotatably secured to said rotor through a self aligning bearing, a stud in the bore of said drive shaft and secured thereto by means for axial movement, a universal joint secured at one end to said rotor and at the other end to said stud, and means for resiliently lifting said rotor into contacting position with said stator stone.

2. In a colloid mill, a longitudinal inlet head, a stator stone secured to said inlet head, a sleeve having an eccentric aperture movably receiving said inlet head, a forked member, a tail rod unitary with said inlet head registering in

said forked member for retaining said inlet head in oscillating position when said eccentric sleeve is rotated, and an angular deflecting hood unitary with said inlet head and stator stone, for deflecting the material being ground, a rotor provided with a rotor stone located beneath said stator, a drive shaft having an axially bored upper portion rotatably secured to said rotor through a self-aligning bearing, a stud in the bore of said drive shaft and secured thereto by means for axial movement, a universal joint secured at one end to said rotor and at the other end to said stud, a coiled spring wound about said stud in said drive shaft and adapted to lift said rotor stone into cooperating position with said stator stone. 5

3. In a colloid mill, a longitudinal inlet head, a stator stone secured to said inlet head, a sleeve having an eccentric aperture movably receiving said inlet head, which said eccentric sleeve is 20 driven by means of gear and pinion, a forked member, a tail rod unitary with said inlet head registering in said forked member for retaining said inlet head in oscillating position when said eccentric sleeve is rotated, a self-aligning rotor 25 supporting a rotor stone beneath said stator, a universal joint engaging said rotor and a main drive shaft, and resilient means on said stator longitudinally movable and urging said stator 30 stone into co-operative engagement with said rotor stone.

4. In a colloid mill, a longitudinal inlet head, a stator stone secured to said inlet head, a sleeve having an eccentric aperture movably receiving said inlet head which said eccentric sleeve is 35 driven by means of gear and pinion, a forked member, a tail rod unitary with said inlet head registering in said forked member for retaining said inlet head in oscillating position when said eccentric sleeve is rotated, a self-aligning 40 rotor supporting a rotor stone beneath said stator, a universal joint secured at one end to a T head drive shaft and at the other end to the said rotor, and resilient means for urging said 45 rotor and rotor stone into co-operative engagement with said stator stone.

5. In a colloid mill, a longitudinal inlet head, a stator stone secured to said inlet head, a sleeve having an eccentric aperture movably receiving said inlet head, which said eccentric sleeve is 50 driven by means of gear and pinion, a forked member, a tail rod unitary with said inlet head registering in said forked member for retaining said inlet head in oscillating position when said eccentric sleeve is rotated, and an angular 55 deflecting hood unitary with said inlet head and stator stone for deflecting the material being ground, a self-aligning rotor supporting a rotor stone beneath said stator, a universal joint secured at one end to a T head drive shaft and 60 at the other end to the said rotor, resilient means for urging said rotor and rotor stone into co-operative engagement with said stator stone and a flinger on said rotor.
